UNITED STATES PATENT OFFICE.

CHARLES I. LAMB, OF NASHVILLE, TENNESSEE, ASSIGNOR TO THE SENG COMPANY,
OF CHICAGO, ILLINOIS, A CORPORATION OF ILLINOIS.

DAVENPORT BED.

Application filed December 4, 1922. Serial No. 604,681.

This invention relates to a folding davenport bed of the type in which the sections are foldable under the seat with a back and seat hinged in the frame and rotatable upwardly 5 and forwardly respectively. Among the objects of the invention are: to provide folding bed bottom sections entirely separate and unconnected with the seat itself; to provide improved locking means for holding the bed 10 bottom structure in raised or unfolded condition; to support some of the bed arm sections from the underside of the seat when the latter is inverted; to provide solidly attached legs for supporting the outermost 15 bed section and for folding these legs under the seat without collapsing them; to provide improved side supporting members for the bed sections upon which they are mounted and movable in the ends of the frame; and 20 in general, to provide the construction herein shown and described.

In the accompanying drawing, Fig. 1 is a side view of one frame end removed of a davenport bed in open position, constructed 25 in accordance with the principles of this invention; Fig. 2 is a similar view but with the bed frame sections in folded position; Fig. 3 is a rear view illustrating the operation of the locking member; and Fig. 4 is a 30 plan view of the bed in open position.

In many davenport beds the sectional bed bottom is attached by links or otherwise to the underside of the seat so that when the seat is raised the bed sections will be unfolded or partially unfolded by the opening 35 of the seat. In such a case the operator must not only raise the seat, but also must partially raise the bed sections which may be of considerable weight; furthermore, this 40 operation limits the folding of the bed sections to certain ways in order to be covered by the seat. In the present invention the seat is first raised and overturned in front of the frame and then by stepping upon a 45 suitable support on the underside of the seat the sectional frame is easily accessible for this unfolding movement which consists not in the overturning of the uppermost section but by raising the outer end of it and pulling 50 it outward; this outward movement being suitably guided by levers and supports

so that as the uppermost section is carried outwardly the other sections will be raised and at least one of them will be suitably supported by the front of the seat itself in 55 this overturned position.

Referring now more particularly to the drawings, end frames 1 are rigidly connected at the back by cross pieces 2 at the front by a front board 3. An upholstered seat 4 is pivotally mounted at the front of the frame by hinging brackets 5, and connecting the lower edge of the front seat and the top of the foot board 3 is a fabric strip or valance 6. At the upper end of the frame 1 a back 7 is so pivoted that it will rest against a top strip 8 in raised position, as shown in Fig. 1 and will engage and cover supporting legs 9 at the rear of the seat 4 in closed position, the legs supporting the outer edge 70 of the seat from the floor when the seat is overturned.

The bed bottom comprises a rear section 10, a short connecting section 11, an intermediate section 12, an outer section 13, and a connecting support 15 between the outer and intermediate sections. When folded these sections lie in the general shape of a letter S, the upper face of the outer section remaining uppermost at all times. To support the bed bottom in the frame there is an angle lever 16 in the form of a bell crank pivoted to the inside of each frame end and one extremity of each lever is pivoted to the end of the rear bed section 10 intermediate the sides thereof and to the other end of the lever is pivoted a slotted link 17. The movement of this link with respect to the lever is limited in one direction by an overhanging lug 18 and the intermediate 85 section 12 has a projecting headed member 19 which moves in a slot 20 of the link 17 in the folding and unfolding movement thereof. These pivoted levers 16 form the only direct connection for mounting the sectional bed bottom in the frame. At the rear of the frame is a loose connection preferably consisting of short chains 21 each connected at one end to the frame 1 and at the other end to the rearmost bed section 10, to 90 limit the upward movement of the bed section. The connecting members 15 at oppo-

- site sides of the bed bottom are connected by oppositely turned channel bars 22 forming a truss for preventing the collapse of the bed bottom, and extending downwardly adjacent each end of the truss thus formed is a projection 23 for engaging a striker plate 24 carried by the seat 4 and preferably at the upper (when inverted) ends of the legs 9. The sections 12 and 13 are therefore supported and braced by the connecting truss which bears upon the underside of the seat directly in line with the supporting legs 9 thereof. At the outer end of the section 13 are fixed supporting legs 25. This outer end of the section 13 also carries a pivoted bail 26 which is rotatable upwardly to form a pillow rest, spring tongue 27 for holding the bed clothes, and handles 28 for raising and lowering the bed sections.
- In order to support the rear section 10 in its raised position, as shown in Fig. 1, a locking device comprising a bail 29 is pivoted at its ends at the front and rear of the frame and rests upon cross braces 30. This bail carries a projection 31 and when rotated upwardly, the projection engages the rear frame of the section 10 and the bail itself engages the central portion of a truss bar 32 which joins the connecting sections 11 to the bed bottom. In order to raise and lower the bail a bar 33 is pivoted to the rear of the bail and has a bent upper extremity 34 which engages over one of the back cross rails 3 where stops 35 are provided for limiting and holding a bar in either position of the bail 29. With this bail in its raised position the rear portion of the bed can not collapse and the bed sections can not be folded. The engagement of the bail with the downward extension of the truss bar 32 and the height of the projection 31 thereon insures that it is sufficiently below the level of the bed bottom to offer no objectionable obstruction to a person sleeping therein.
- Attached to each side of the frame is a bar 36 with an offset 37 at the top where it is connected to the frame, the lower end being free from any connection and acting only as a guide for the bed sections. Extending from the underside of the seat is a short leg 38 on each side thereof which is adapted to engage the shoulder 37 of the bar 36 when the seat is overturned, thereby rigidly supporting the seat in this position.
- Also attached to the underside of the seat and preferably about midway of the ends is a plate 39 forming a step upon which the foot or feet may rest in folding and unfolding the bed bottom.
- In order to space the bed sections apart in their folded position, the rear section 10 is provided with a rigid upright arm 40 on each side thereof which is adapted to engage the intermediate section 12. These arms are only at the side of the section and are with-

in the frame so that they offer no objectionable obstruction to a person sleeping in the bed. When the bed sections are folded the lowermost section rests upon the bail 29 and upon the cross pieces 30, and the legs 25 are disposed at the front just behind the front board. Plenty of space is provided for bedding or for a mattress which is usually attached to or carried by the bed bottom which comprises a spring supported fabric 41 carried by the bed bottom frames, the bed clothes also assuming the S-shaped folded condition of the bed bottom sections.

In operation, assuming the seat and back to be in closed position, the back is first rotated upwardly about its pivot to the rest position, as shown in Fig. 2. The seat is then overturned forwardly about its pivots until the feet 9 thereof rest upon the floor. This forms a solid support for stepping upon the plate 39 on the underside of the seat, for grasping the handles 28 attached to the front edge of the front bed section 13. This section is raised until the legs 25 will clear the front board and then the bed frame is pulled upwardly and outwardly as the operator steps down and off of the plate 39. This will raise and swing outwardly the intermediate section 12 carrying the slotted links 17 therewith until the overturned lug 18 reaches its limiting position in engagement with the intermediate of the lever 16. The lowering movement of the outer sections 13 and 12 in allowing them to swing into place raises the inner end of the lever 16 and with it raises the inner section 10 and the connecting section 11. During this movement of the bed bottom the headed projection 19 has moved in the slot 20 from one end, as shown in Fig. 1, as the bed bottom swings into place the supporting and connecting truss member 11 rests upon the abutment provided for it at the outer edge of the overturned seat thus supporting the adjacent ends of the bed sections 12 and 13 and the outer end of the section 13 is supported by the leg 25. The inner end of the section 12 is supported by the slotted members 17 and the levers 16, the other ends of the levers 16 and the inner end of the inner section 10 being prevented from upward movement by the chains 21. To prevent the downward movement of the inner section 10 the locking bail 29 is moved upwardly as previously described until it engages the truss 32 and the rear of the section 10.

In folding the bed the operation is reversed; the bail is first turned downwardly, the outer sections 12 and 13 are raised and are held in alinement by the engagement of the connecting member 15 as these sections tend to swing in the opposite direction, carrying with them the slotted links 17 which turn about their pivots on the lever 16 the headed projections 19 sliding in the 130

slots 20. At an intermediate position approaching the vertical, the bed sections 12 and 13 break inwardly at their point of connection and fold over in the back of the 5 frame, the levers 16 at this time swinging downwardly about their pivots until the bed section 10 is in its lowermost position. The bed sections will then assume the positions shown in Fig. 2 whereupon the seat is turned 10 back into the frame and the back rotated downwardly against the legs 9 in this position.

I claim:

1. In a davenport bed, a frame, a sectional 15 folding bed bottom supported therein, a seat invertibly mounted at the front of the frame and having no connection with the bed bottom, and a step mounted on the underside of the seat to provide a foot support for an operator in reaching over the 20 seat to unfold the bed bottom.

2. The combination with a supporting frame, of a sectional bed bottom mounted therein, a lateral guide for the bed bottom in 25 its folded position having an offset adjacent its upper end, and a seat pivotally mounted at the front of the frame and having no connection with the bed bottom provided with a projection at each side thereof for 30 engaging the offset of the said guide to support the seat in closed position.

3. In a davenport bed, a frame, a sectional bed bottom of three or more sections mounted 35 for folding therein, comprising a depending truss member between the two outermost sections, a seat invertibly mounted at the front of the frame independent of any connection with the bed bottom having a fixed support at its outer side when inverted, 40 and means on the underside of the seat at the outer edge thereof for providing an engaging surface for the truss member.

4. In a davenport bed, a frame, a sectional folding bed bottom mounted therein 45 and comprising a depending truss member intermediate the ends thereof, an invertible seat having a fixed support at its outer side and contact plates on the upper surface thereof when inverted, and a support for 50 one of the outer bed sections when the bed bottom is extended, the truss member engaging the plates on the seat for supporting the intermediate portion of the bed bottom.

5. In a davenport bed, a sectional folding 55 bed bottom, a frame therefor, and means for pivotally mounting and supporting the bed bottom in the frame, said means comprising an angle lever pivoted at each side of the frame, one end of which is connected to the rear bed section, and a slotted member pivoted to the other end of the angle lever and having a sliding connection with another bed section.

6. In a davenport bed, a frame, a sectional 60 folding bed bottom, an angle lever at each

side of the frame, one end of which is pivotally connected to the rear bed section, and a member pivoted to the other end of the angle lever having a stop for limiting its movement in one direction, and having a 70 slot engaged by a projection from a bed section remote from the rear bed section.

7. In a davenport bed, a frame, a sectional bed bottom foldable in the frame and comprising three or more sections, lever pivoted 75 at one end to the rear section and intermediate its ends to the frame, a supporting link pivoted to the other end of the lever and having a pin and slot engagement with the second section from the said rear section. 80

8. In a davenport bed, a frame, a seat pivoted at the front thereof and independently supported in open and closed position, a foldable bed bottom comprising a plurality of sections, and supporting means comprising a supporting lever at each side of the frame connected to the rear section and with a pivoted extension having a sliding connection with the third section therefrom for spacing and folding the sections independently of the seat in the form of an S below the seat. 85

9. In a davenport bed, a frame, and a five section bed bottom foldable in the form of an S in the frame, means for mounting the sections in the frame only comprising a lever at each side having a pivoted connection with the lowermost section and an extension having a pivoted and sliding connection with the third section, the three uppermost sections being movable outwardly and upwardly to raise the other sections into alignment therewith through the said mounting means. 90

10. In a davenport bed, a frame, a sectional bed bottom, means for mounting the bed bottom in the frame only, said means comprising a single lever at each side of the frame having a pivoted connection at one end with one of the sections, and a pivoted extension at the other end of the lever having a pivoting and sliding connection with another section, this last named section and two upper sections being movable bodily upward and outward substantially into alignment to turn the said extension and lever for raising the rear section and moving all the sections into alignment to form the bed. 105

11. In a davenport bed, a frame, a sectional folding bed bottom, one of the sections comprising a transverse truss bar, means for mounting the rearmost sections for raising movement when unfolded, and a locking bail movable to an upright position for engaging the underside of the said truss bar to hold the bed bottom in a bed position. 110

12. In a davenport bed, a frame, a sectional bed bottom foldable therein, means for mounting the sections to swing upwardly in the frame when unfolded, a locking bail for engaging beneath some of the sections for 115 125 130

holding them in raised position, and means at the back of the frame for operating the locking bail.

13. In a davenport bed, a frame, a sectional bed bottom foldable within the frame, means for mounting the sections for raising movement in the frame when unfolding, a

bail pivoted in the frame and extending transversely to hold the rear section in raised position when unfolded, and a chain ¹⁰ attached to the frame and the rearmost section for limiting the upward movement thereof.

CHARLES I. LAMB.
